UNITED STATES PATENT OFFICE.

ALEXANDER F. WARD AND GEORGE MEAD, OF DETROIT, MICHIGAN.

ELEVATOR.

SPECIFICATION forming part of Letters Patent No. 355,285, dated December 28, 1886.

Application filed February 25, 1886. Serial No. 193,138. (No model.)

To all whom it may concern:

Be it known that we, ALEXANDER F. WARD and GEORGE MEAD, of Detroit, in the county of Wayne and State of Michigan, have invented new and useful Improvements in Elevators; and we hereby declare that the following is a full, clear, and exact description thereof, reference being had to the accompanying drawings, which form a part of this specification.

This invention relates to a new and useful improvement in devices especially designed for locking elevator hatch-doors against accidental displacement.

The object of the invention is to provide means for locking hatchway-doors of the trap-door style particularly, and in providing means for opening the doors up or down in the travel of the elevator; and the invention consists in the peculiar construction and application of mechanism arranged with a counter-balance to the door that will compel such door to assume its horizontal position, closing the hatchway immediately after the passage of the elevator, all as more fully hereinafter set forth.

Figure 1 is a perspective view of a hatchway and platform-elevator provided with our improved device. Fig. 2 is a vertical section showing the elevator as in the act of passing through the hatchway and opening the trap. Fig. 3 is a diagram section. Fig. 4 is a detailed perspective of one of the lock-levers.

In the accompanying drawings, which form a part of this specification, A represents a hatchway through which the elevator B is designed to pass, as in the ordinary manner. In the construction shown the guide-posts for the elevator are at the center of the sides of the hatchway, and hence our device is arranged in connection therewith for operating the trap-doors C, which are secured to a rock-shaft, D, properly journaled across one side of the hatchway-opening, and preferably below the level of the floor. Upon one end of this shaft is secured a pinion, E, which meshes with a similar pinion, F, properly journaled upon a stub-shaft, G, projecting laterally from the side of the hatchway casing or frame, and upon this shaft G is also journaled a semicircular plate, H, between which and the outer face of the pinion F is also journaled upon said shaft a rocker-arm, I, said rocker-arm and plate be-

ing rigidly secured to the pinion F, so as to turn therewith. In each end of the rocker-arm is secured an anti-friction pulley or wheel, a a'.

J is a lever, one end of which is fulcrumed, as at d, while the opposite end, when in the position shown in Fig. 3, rests upon the anti-friction rollers a a', and this lever is provided with a weight, K, and the plate H has also pivotally secured to one corner a counter-weight, L, both of these weights being sufficient to compel the doors to assume a horizontal from a vertical position, as hereinafter set forth.

At the opposite side of the hatchway to that occupied by the shaft D is journaled in proper bearings a rock-shaft, M, to which, upon opposite sides of the adjacent elevator-guide, are secured the stops N O, the former of which has formed in its outer end a suitable hole to admit of the pin or stud P, which projects laterally from the side of the lever R, which latter is fulcrumed to the adjacent side of the post by means of a suitable bolt, b, which passes through the slot c in the upper end of the lever, as shown.

In practice, the parts being in the position shown in Fig. 3, with the elevator below the floor, as the elevator rises an arch-piece, S, upon its top comes in contact with the lower face of one of the doors, while a bar, T, upon its side at the same time impinges against the face of the curved and lower end of the lever R, pushing such lever outward, causing the stops N and O to turn into nearly a vertical position. In the progress of the car the doors are opened, as in Fig. 3, from a horizontal to a vertical position, as shown in Fig. 1. The doors in assuming this position have necessarily turned or partially rotated the rock-shaft D, and by the means herein described cause the plate H to assume the position shown in the same Fig. 1, with the end of the lever J resting now upon the anti-friction roller a' of the rocker-arm. After the elevator has passed the free ends of the doors the counter-weight K upon the lever performs its function by forcing or bearing down upon such anti-friction roller, and thereby compelling a retrograde movement of the parts, the doors gradually closing from the vertical to the horizontal position and resting upon the ends of the stops

NO, which have by gravity fallen forward in the line of radial travel of the door immediately after the passage of the elevator, and in this position the trap is held against accidental displacement or opening in case any one should step upon it. As the elevator descends the bar T impinges against the upper part of the lever R, forcing it and the stops outwardly, free from engagement with the door, which is then free to be opened downwardly by the elevator. In opening the doors downwardly the connected mechanism has assumed a position the reverse to that shown in Fig. 1, with the end of the lever J resting upon the anti-friction wheel a. The elevator having passed the lower end of the door, the weight L causes the shaft D, through the mechanism hereinbefore described, to partially rotate. The door radially swinging upward, the corner d' of the cut-away portion of the door pushes the stops and lever outwardly until the door has swung past, when the stops again assume their original position, the door falling back upon them.

25 We design to employ similar stops at the outer corners of the doors, although but two are shown located at the center of the hatchway.

It is obvious that our device can advantageously be attached to any and all kinds of trap swing-doors without departing from the spirit of our invention. It will also be observed that, where the room will admit of it, the pinions E and F may be omitted, the plate H and rocker-arm I being in this case connected directly to the shaft D.

The weight L is a counter-weight to the door, while the function of the weight K and lever J is to compel the doors to close from either direction, and to hold them in a normal horizontal position, the end of the lever resting upon the two fulcrums a a' in a horizontal plane.

What we claim as our invention is—

1. The combination, with the hatchway and elevator-car, of the rock-shaft M, stops carried thereby, and a lever connected with one of said stops and operated by the passage of the car, substantially as and for the purposes specified.

2. In a hatchway-elevator provided with a swinging door or doors secured upon a rock-shaft, in combination with a weighted lever and rocker-arm, the latter being provided with a bearing at each end for the free end of the lever, and connections, substantially as described, between said rock-shaft and rocker-arm, whereby the latter is operated by the movement of the former, substantially as set forth.

3. The combination, with the hatchway, rock-shaft D, journaled therein, and doors carried by said rock-shaft, of the lever J, plate H, and rocker-arm I, said shaft and rocker arm all arranged and operating substantially as and for the purposes specified.

4. The combination, with the hatchway, the rock-shaft journaled therein, and the door secured to said rock-shaft, of the lever J, semicircular plate H, connected and operated by said rock-shaft, weight L, and rocker-arm I, provided with rollers a a', substantially as and for the purposes specified.

5. The combination, with the hatchway, the rock-shaft D, journaled therein, and the doors carried by said rock-shaft, of the pinions E F, semicircular plate H and rocker-arm I, provided with rollers a a' and secured to said pinion F, the pivoted weighted lever J, and weight L, all substantially as shown and described.

ALEXANDER F. WARD.
GEORGE MEAD.
